[57] CLAIM

The ornamental design for an athletic shoe, as shown and described.

DESCRIPTION

FIG. 1 is a right side elevational view of an athletic shoe showing my new design;
FIG. 2 is a left side elevational view thereof;
FIG. 3 is a front elevational view thereof;
FIG. 4 is a rear elevational view thereof;
FIG. 5 is a bottom plan view thereof;
FIG. 6 is a right side elevational view of another embodiment of my new design of FIGS. 1-5, all other views thereof are substantially similar to FIGS. 2-5.
